A. E. Sumersille

By B. P. Johnson

Attorney

UNITED STATES PATENT OFFICE.

ALANO E. SUMERSILLE, OF SAN JUAN, PORTO RICO.

CHECK.

1,282,311.

Specification of Letters Patent. Patented Oct. 22, 1918.

Application filed July 18, 1918. Serial No. 245,528.

To all whom it may concern:

Be it known that I, ALANO ERLE SUMERSILLE, citizen of the United States, residing at San Juan, Porto Rico, have invented certain new and useful Improvements in Checks, of which the following is a specification.

My invention relates to improvements in checks, for use in connection with banks, and other business purposes.

10 An important object of the invention is to provide means for utilizing the location of the signature of the maker of the check, to prevent the check being raised.

15 A further object of the invention is to provide a check of the above mentioned character, which may be made out rapidly, and which is clear in meaning, when made out.

20 Other objects and advantages of the invention will be apparent during the course of the following description.

In the accompanying drawings forming a part of this specification and in which like numerals are employed to designate like parts throughout the same,

25 Figure 1 is a side elevation of a check embodying my invention, made out for less than \$100,

Fig. 2 is a similar view of the check, showing the same made out for less than \$1000,

30 Fig. 3 is a similar view of the check, showing it made out for less than \$10,000, and,

Fig. 4 is a similar view of the check, showing the same made out for less than \$100,000.

In the drawings, wherein for the purpose of illustration is shown a preferred embodiment of my invention, the numeral 5 designates a check, as a whole, having a centrally arranged space 6, having printed therein the name 7 of the bank, together with the address 8, and a line 9, for the reception of the date. The central space 6 is horizontally ruled beneath the line 9, providing a line 10, receiving the name of the payee, such line being designated "Pay to the order of". Beneath the horizontal line 10, is a second horizontal line 12, for the reception of writing, indicating the amount for which the check is drawn. Disposed near the top of the space 6, and at one end thereof, is a line 14, for the reception of the number of the check, such line being designated "No."

In accordance with my invention, the location of the signature of the maker of the check is employed to designate the amount for which the check is drawn, thereby preventing the check being raised.

The upper portion of the space 6 is horizontally ruled, providing a line 16, designated "Sign here for less than \$100" and above this designation is a space 17, for the reception of the signature of the maker of the check. At its right end, the space 17 is vertically ruled, providing columns 19 and 20, for receiving numerals, indicating the number of dollars and cents, for which the check is drawn. These columns are designated by the dollar and cent marks.

At the left hand end of the check, a space 21 is provided, which is transversely ruled by lines 22 and 23. These lines are designated "Only 3 figures" and "Hundred dollars" respectively. At its inner end, the space 21 is transversely ruled by a line 24, designated "Only 4 figures thousand dollars." This designation, however, is inverted with respect to the designation of the lines 22 and 23. Between the end transverse lines, the space 21 is transversely ruled by a plurality of lines 25, for the reception of the name of the maker of the check. When the check is turned so that the designations of lines 22 and 23 may be read, the numerals 26 appear at the right ends of these lines and designate the same, such numerals being arranged in numerical order and running from 1 to 9 inclusive. At the opposite ends of the lines 25 are disposed numerals 27, which serve to designate the same. These numerals are arranged in numerical order and run from 1 to 9 inclusive. The numerals 27 are inverted with relation to the numerals 26, and are adapted to be read, when the check is inverted, so that the designation of the line 24 may be read. At the opposite ends of the lines 25, the space 21 is longitudinally ruled by lines 28, providing longitudinal columns 29 and 30, for the reception of the numerals designating the number of dollars and cents for which the check is drawn. The numerals 26 and 27, when the check is held in the proper position, are arranged to the extreme left in the column 29, and constitute the first number in the amount which designates the number of dollars for which the check is drawn. It is thus seen, that while these numerals are printed upon the check when it is made, they serve to designate the signature lines 25, and also constitute the first numeral in the number indicating the amount for which the check is drawn.

At the opposite end of the check, is a space 31, provided near one end with longi-

tudinal lines 32, designated, "Only 5 figures" and "Ten thousand \$." At the opposite end of the space 31, there are longitudinal lines 33 and 34, designated "Only 6 figures" and "Hundred thousand \$." The designations for the lines 33 and 34 are inverted with respect to the designations for the lines 32, and are adapted to be read, when the check is inverted. When the check 5 is held in the proper position to be read, the numerals 35 are located at the right of transverse lines 36, and serve to designate them. These numerals are arranged in numerical 10 order. At the opposite ends of the lines 36, 15 are numerals 37, which are inverted with respect to the numerals 35. The numerals 37 are arranged in numerical order, and serve to designate the lines 36. These numerals 37 are read with the designations for the lines 20 33 and 34, when the check is inverted. The spaces at the opposite ends of the lines 36 are transversely ruled, by lines 38, providing columns 39 and 40. The numerals 35 and 37 are arranged in the columns 39, and 25 when the check is held in a position so that either set of numerals is being read, such numerals will be located in the extreme left of the column 39, and constitute the first numeral in the number, designating the 30 amount for which the check is drawn.

Attention is now called to the check shown in Fig. 1. This check is made out for \$8.92, and the maker "Richard Roe" has signed the same in the space 17. The amount in figures is filled in the columns 19 and 20, and the amount of the check is also indicated in writing, upon the line 12. As the spaces at the ends of the check are not used, diagonal lines are drawn across the lines 25 and 36, 35 clearly indicating the same.

The check shown in Fig. 2, is made out for \$615.78. The maker "Richard Roe" signs the check in the space 21, upon the line 25 designated by "6" when the check is held in 40 the position to read the designations of the lines 22 and 23. The maker of the check inserts in the column 29, behind the "6", "15" and also inserts "78" in the column 30, these figures indicating the amount of the check. 45 The amount of the check is also indicated, in writing, upon the line 12. Lines are drawn across the spaces 17 and 31, to indicate that they are not used.

The check shown in Fig. 3, is made payable to "John Doe" for the sum of \$5016.18, 50 which is indicated in writing upon the line 12. The check is now held so that the designations for the lines 22 and 23 are inverted, while the designation for the line 24 is arranged for reading. The maker "Richard Roe" now signs in the space 21, upon the line 25, designated by "5" to the right of the line, as the check is being held. The maker now inserts to the rear of "5", "016" in the 60 column 29, and "18" in the column 30. 65

These figures make \$5016.18, indicating the amount of the check. The maker also draws lines through the space 17, and over the lines 16.

In Fig. 4, the maker's name, "Richard 70 Roe" is signed in the space 31, upon the line 36, designated "2". Opposite this signature to the right, and in the column 39, the amount "20,000" appears, as is obvious.

If it is desired to make a check for 75 \$100,000, the check would be inverted, and the maker would sign his name upon the proper line 36 of space 31, as is obvious.

It is to be understood that the form of my invention herewith shown and described 80 is to be taken as a preferred example of the same, and that various changes in the arrangement and order of parts, may be resorted to, without departing from the spirit 85 of my invention or the scope of the subjoined claims.

Having thus described my invention what I claim is:

1. A check of the character described having a plurality of spaced lines for the reception 90 of the signature of the maker of the check, said spaced lines being provided with numbers which constitute a portion of the amount for which the check is made out.

2. A check of the character described having a plurality of spaced lines for the reception 95 of the signature of the maker of the check upon a selected line, said lines being provided near corresponding ends with numerals which are arranged in numerical 100 order, said check being ruled longitudinally of the numerically arranged numbers to provide spaces for receiving the figures indicating the amount for which the check is made, the number of the selected line constituting a portion of the amount of the check.

3. A check of the character described having a plurality of spaced lines for the reception 110 of the signature of the maker of the check upon a selected line, said check being ruled at corresponding ends of the lines for providing a plurality of columns for receiving the amount of the check, and numerals serving to designate the spaced lines and arranged in one of said columns whereby a selected numeral constitutes a portion of the amount of the check.

4. A check of the character described having a plurality of spaced lines for the reception 115 of the signature of the maker of the check upon a selected line, said check having a pair of sets of numerals arranged at the opposite ends of said lines and serving to designate the lines, the numerals in each set being arranged in numerical order and the numerals in one set being inverted with respect to the numerals in the other set, said check being ruled at the ends of said lines 120 to provide columns arranged at substan- 125

tially a right angle with relation thereto, the inner columns receiving the numerals, a selected numeral constituting a part of the amount of the check.

5. A check of the character described having a central portion ruled for the reception of the name of the payee of the check and other data, said check being provided in the central portion thereof with a space for the 10 reception of the signature of the maker of the check and spaces for the reception of the amount of the check, said spaces having designations indicating the maximum amount to be inserted therein, said check being provided at its ends with two sets of 15 lines for the reception upon a selected line of the signature of the maker of the check, the lines in each set being provided with numbers a selected one of which constitutes a portion 20 of the amount of the check, the sets of lines having designations indicating the maximum amount to be filled in in connection with a selected line.

6. A check of the character described having a central portion ruled for the reception 25

of the name of the payee of the check and other data, said check being provided in the central portion thereof with a space for the reception of the signature of the maker of the check and spaces for the reception of the amount of the check, said spaces having designations indicating the maximum amount to be inserted therein, said check being provided at its ends with two sets of 30 lines for the reception upon a selected line of the signature of the maker of the check, the lines in each set being provided at corresponding ends with numbers which are numerically arranged, the lines in one set being disposed at substantially a right angle to the lines in the other set, said check being ruled at corresponding ends of the lines in each set for forming a plurality of columns, one column receiving the numbers which designate the lines, the sets of lines having designations indicating the maximum amount to be inserted in connection with a selected 35 line of either set.

In testimony whereof I affix my signature.

ALANO E. SUMERSILLE.
